UNITED STATES PATENT OFFICE.

RICHARD BORLASE MATTHEWS, OF EAST GRINSTEAD, ENGLAND.

MANUFACTURE OF BOOKS.

1,391,199.

Specification of Letters Patent. Patented Sept. 20, 1921.

Application filed January 9, 1920. Serial No. 350,324.

To all whom it may concern:

Be it known that I, RICHARD BORLASE MATTHEWS, subject of the King of Great Britain and Ireland, and resident of Greater 5 Felcourt, East Grinstead, in the county of Sussex, England, have invented certain new and useful Improvements in the Manufacture of Books, of which the following is a specification.

10 This invention has reference to the manufacture and use of books, and to the printing of the same, and is applicable to all kinds and classes of books but more particularly to reference books, for instance of the kind 15 or class to which technical pocket-books or data books belong.

In books in which a wide variety of subjects, or branches of a subject are dealt with, matters which are intimately associated in 20 their nature often occur at widely separated parts of the book. Not only does this often impede the reading up of some specific subject, owing to the inconvenience of having to turn backward and forward constantly 25 for reference, but the user frequently only requires on one class of work, some few particular sheets or pages from different parts. These pages it would often be very 30 convenient to have assembled together as a small separate book for the time being, especially if the user did not wish to carry the whole book with him, on a journey for instance.

If the books were made on the well-known 35 loose-leaf principle, this difficulty would largely disappear since the requisite pages could be easily taken out as required, but the objections to this are that the book itself has not then the convenience of an ordinary 40 book, besides which the loose-leaf book has to be printed and made up in a special manner. It is for instance no longer possible to follow the ordinary system which enables several pages to be printed at once, or in 45 multiple, on a large sheet, and then folded over into sections or pages which are stitched and bound together.

Now the object of this invention is to provide a book which is printed on large or multiple sheets, which are afterward folded and bound in the ordinary way as referred to, but in which the leaves or pages are adapted

to be removed and to be reassembled together, conveniently and with accuracy of registration in an ordinary loose-leaf cover 55 or binder, so as to form a small separate book as it were, containing all the pages relating to the subject immediately in hand.

To this end, according to the invention, the pages or leaves are printed so that the 60 matter instead of being approximately central, lies somewhat toward the outer edge of the page, thus leaving an extra wide margin at the inner edge, namely the edge next the stitching and binding. Suitable gage 65 marks or centers are printed in this margin, which when the page is detached, should be punched or perforated to correspond to the loops, claws or fastenings of the loose-leaf binder, such gage marks being of course in 70 fixed relationship to the type matter.

Border lines or rulings may also be printed around the edges, to serve as guides for neatly trimming the pages after detachment, to exactly suit the particular loose-leaf cover in which they may be destined 75 to be placed. A similar line or ruling may be provided in the margin near the inner or binding edge to show where the pages should be severed, and to insure that they will all 80 match properly when assembled in the binder. Provision may also be made for the positioning of indicating tabs, by suitably shaped printed markings on the margin of 85 the paper.

In addition, the line of severance or detachment may be perforated or indented so that it constitutes a line of weakness, and permits the page to be readily detached from the book without damaging it, and 90 without any necessity for slitting or cutting it separately.

In order that the invention may be clearly understood and readily carried into effect reference will now be had by way of example to the accompanying drawings.

Figure 1 shows one of the improved pages, as it appears when still forming part of the large sheet or folio.

Fig. 2 shows a book made up of such 100 pages bound in the ordinary way.

Fig. 3 shows a printed sheet before being folded, cut and bound in book form.

Fig. 4 is a perspective view showing the

same sheet after being folded and cut, and prior to being bound in permanent form in a book.

Fig. 5 is a perspective view of a book in which the sections have been permanently bound, one of the pages being shown in dotted lines after being separated from the book along the indication adjacent the permanent binding edge.

10 As will be seen from the drawings, the pages *a* are formed from a large sheet *k* (Fig. 3) printed in multiple form and afterward folded along the dot and dash lines *l*, *l*, then cut or trimmed to form a section 15 as shown in Fig. 4. The section thus formed is then bound in permanent book form in the usual well known manner and as shown in Fig. 5, the binding edges being illustrated by dotted lines *m*, *m*, in Figs. 3 and 4.

20 The dotted line *b* (Fig. 1) represents the boundary of the space occupied by the letter press on the page and is not, of course, a line printed on the page. It will be seen that such letter press lines lie toward one 25 side of the page in the manner above referred to leaving a wide margin on the left or inner side.

c c are the gage marks or centers which are printed in the wide or inner margin for 30 facilitating the correct punching of the holes for the loose-leaf binding loops or claws. Such punching may be done either after the sheets are detached, or it may be done by the manufacture before the binding operation, for instance as shown at *c¹* on the right of Fig. 2.

d d is a border line which is also printed around the outer edge of the page to facilitate trimming if required.

40 *d¹ d¹* are marginal tabs of the usual kind for indicating the contents. Such of these as are not required can be cut off by user and the remaining tab or tabs may be stiffened by gumming an extra piece of 45 paper or cardboard behind it.

The line *e* on the extreme left simply shows the position at which the whole sheet is folded to form a section ready for binding.

f is a detachment gage or a line of weakness, consisting of marks or indentations or semi-perforations which may be formed down the left hand margin and may be produced at the same time as the printing, by the use of a suitable rule or slip. Of course 55 lines of ordinary perforations like those of postage stamps may be used if desired.

It will be understood that the wide margin next the left or binding edge, allows a sufficient amount of margin on the detached 60 sheet, and also leaves a spare piece or strip *g* (Figs. 1 and 5) still in position undisturbed in the binding of the book, thus preventing such binding being weakened or

coming to pieces owing to the removal of leaves therefrom.

65

Besides this, although the book can be printed and bound according to the ordinary trade methods for books made up of assembled sections, yet any page can readily be taken out and used for loose-leaf binding. This can be done by slitting or detaching them along the line *f* after which they can be accurately punched or perforated by aid of the gage marks or centers printed thereon (if this has not been done already) 70 and assembled into a loose-leaf cover or holder without difficulty and with the printed matter on all the pages in exact register. Moreover by cutting the pages along the trimming lines, all their edges can be 75 made to match exactly, and have a regular margin all around.

75

Although only three gage or center marks *c* are shown in Fig. 1, yet a number may be provided to suit different makes of loose-leaf binder. Hence the user can select which binder he prefers and by keeping to the corresponding marks, can still insure a proper 80 registering of the pages, when bound in loose-leaf fashion.

85

The detachment gage line *f* although spoken of as a line of weakness may be simply a printed line, in a position in which it can be conveniently slit by the user when it is required to be detached.

90

The aforesaid gage-marks or centers and trimming guides or border lines can all, as will be readily understood, be printed at the same time as the letter press, and do not necessarily involve any additional printing 100 operation.

100

Usually it is sufficient to print them on the right-hand pages, although they may be printed on the left hand pages, or on both, if desired.

105

What I claim as my invention and desire to obtain by Letters Patent is:—

1. A book made up of pages printed in multiple form, folded, cut and adapted to be permanently bound in sections in a book, 110 each of said pages having a narrow blank outer binding edge formed by a narrow strip along one side, sewn and permanently bound with the page in book form, an indication on each page parallel with said binding edge 115 along which the remaining portion of the page may be separated from said strip, and markings adjacent said indication serving to enable the separated portion of the page to be accurately perforated and filed away 120 in a loose leaf binder, each of said pages having letter press only in a space inclosed by the edges of the sheet to be separated, for the purposes set forth.

120

2. A book made up of pages printed in 125 multiple form, folded, cut and adapted to

be permanently bound in book form, each of
said pages having an outer binding edge and
an inner binding edge arranged side by side
on one side of the page, and separated from
5 one another by a row of perforations, the
outer binding edge being permanently
bound with the page in book form, while the

inner binding edge is provided with spaced
perforations serving when the page is sep-
arated along the perforations between the 10
binding edges, to enable the separated page
to be accurately filed in a loose leaf binder,
for the purposes described.

RICHARD BORLASE MATTHEWS.
